A. GIBSON

COMBINED FLOAT AND PADDLE FOR USE WHILE BATHING

Filed April 5, 1924

Inventor:

Andrew Gibson
J. C. Chas & Reeder
attorney.

UNITED STATES PATENT OFFICE.

ANDREW GIBSON, OF TURRAMURRA, NEW SOUTH WALES, AUSTRALIA.

COMBINED FLOAT AND PADDLE FOR USE WHILE BATHING.

Application filed April 5, 1924. Serial No. 704,464.

To all whom it may concern:

Be it known that ANDREW GIBSON, a subject of the King of Great Britain and Ireland, residing at Kingston, Gilroy Road, 5 Turramurra, in the State of New South Wales, Commonwealth of Australia, has invented certain new and useful Improvements in a Combined Float and Paddle for Use While Bathing, of which the following 10 is a specification.

This invention relates to a float and paddle device for use while bathing or swimming and the object of the invention is to provide a device by means of which one 15 can keep oneself afloat and at the same time propel oneself through the water. The device may also be used in the surf.

The device comprises a shaft with a paddle at each end and a float in the middle. 20 The float consists of an outer covering of fabric material such as canvas or the like which is attached to and surrounds the shaft. This outer covering contains an inflatable bladder which may be of rubber 25 or the like. The inflatable bladder is constructed with a recess which enables it to envelope the shaft. The outer covering may be filled with kapok or other buoyant material in lieu of the compressed air contained within the bladder.

The paddle blades may be an integral part of the shaft or may be affixed thereto in any well known way.

In the drawings:—

35 Figure 1 is a perspective view of the device showing the bladder inflated.

Figure 2 is a sectional perspective showing the construction of the bladder or rubber bag. The outer covering or canvas bag 3 is situated at the middle of the shaft 4 and 40 is secured thereto at 5 by cord bindings or the like. Through an opening (not shown in the drawings) similar to that in the cover of a foot ball the inflatable bladder 6 is inserted, and inflated by means of the 45 usual tube 7.

The bladder is constructed with a recess 8 to enable it to envelope the shaft. The paddle blades 9 are shown attached to the shaft 4 by bolts 10, but they may be an integral part of the shaft, which can be in 50 two sections united at the middle.

In use the device is gripped on each side of the central float so that by alternately dipping and pulling the blades the operator may be propelled through the water.

I claim:

A combined float and paddle device comprising a shaft with blades at each end a centrally positioned float consisting of an 60 outer covering of fabric material containing an inflatable bag adapted to envelope the shaft.

In testimony whereof he has affixed his signature in presence of two witnesses.

ANDREW GIBSON.

Witnesses:

T. C. ALLEN,
G. GARDNER.
